FLEXIBLE ELECTRIC CONDUCTOR

Horace A. Staples, Plainfield, N. J., assignor to
 Phelps Dodge Copper Products Corporation,
 New York, N. Y., a corporation of New York

Application November 10, 1933, Serial No. 697,369

12 Claims. (Cl. 173—13)

My invention relates to electrical conductors and more particularly to a flexible electrical conductor cable designed for the transmission of electrical power by means of very high voltages. 5 Hollow conductors have been used for the purpose because such conductors are desirable in that they all tend to reduce the corona losses. All of these hollow conductors, however, have certain inherent defects and the object of this 10 invention is to produce such a cable without these known defects.

One of the prime objects of this invention is to produce a cable with concentrated metallic content near the outside circumference of the cable 15 with a minimum of weight of the cable as a whole and the production of a hollow core which resists collapse due to radial stresses caused by tension of the cable.

A further object is to produce a cable of large 20 diameter and a relatively small current carrying capacity that will be flexible and easily handled in the field with a low manufacturing cost.

The foregoing and other features of my invention will now be described in connection with the 25 accompanying drawing forming part of this specification in which I have represented my hollow cable in its preferred form after which I shall point out in the claims those features which I believe to be new and of my own invention.

30 In the drawing:

Figure 1 is a side view of the wire forming the core to my cable.

Figure 2 is a cross section along the line 2—2, Figure 1.

35 Figure 3 is a cross section similar to that shown in Figure 2 with the addition of solid wires stranded on the core.

Figure 4 is a cross section similar to that shown in Figure 3 with the exception that the stranded 40 wires are hollow.

Figure 5 is a cross section of my cable with some of the stranded wires being hollow and of larger diameter than the remaining wires. This is just prior to the passing of the cable through 45 the closing die of a strander.

Figure 6 is a cross section of my cable similar to that shown in Figure 5 after the cable has passed through the closing die of the strander, showing how the hollow cables are compressed 50 into position whereby they hold the loops of the core against longitudinal displacement along the axis of the cable.

Figure 7 is a broken section at right angles to Figure 6 showing the compressed part of the 55 hollow conductor embracing the loop.

Figure 8 is a cross section of my cable in a preferred form.

In carrying out my invention I provide a core comprising a continuous wire 10 formed into a helical shape, the helix being of the same pitch and same diameter as the strand to be laid upon the said core. At intervals I provide circular loops 11 spaced along the helix, with the plane of the loops perpendicular to the axis of the helix. The outside diameter of the loops is the same 10 as the inside diameter of the helix. All of this is readily apparent by referring to Figures 1 and 2. As may be readily understood, I intend to form the loops 11 integral with the helical wire 10. 5

It is upon these loops of the helical core that 15 I strand the wires 12 conforming to the pitch and diameter of the helix of the core wire. See Figure 3. It is obvious that with this construction that if radial stress is applied to the loop 11, through tension on the cable, the portions 20, 21 20 of the core wire, shown in Figure 1 may tend to move so that they overlap each other. This movement, however, is resisted by the wires 13, 14 adjacent the wire 10 as shown in Figure 3 and the arch action of all the wires in the layer of the 25 strand, so that radial collapse of the loop is prevented.

To provide against the deformation of the loops in a longitudinal direction, I may include hollow 30 wires 15 among the wires of the strand, these 30 wires being of larger diameter than the rest of those in the strand, so that while they lay, as shown in Figure 5 before they enter the closing die of the stranding machine, the closing die compresses these wires into the final position 35 shown in Figures 6 and 7 so that the loop 11 is pressed into the hollow wire 15 causing the wire 15 to lock the loop 11 against longitudinal deformation.

In Figure 8 I show a cross section of a typical 40 cable constructed after my invention. In this preferred presentation I show my core made of an integral wire formed into loops and helix with a layer of wires, both hollow and solid stranded over the loops and parallel with the helical wire 45 and an outer surface of high electric conductivity comprising a plurality of individual conductors stranded thereupon. It is perfectly obvious that I may use only one strand upon my core, and that strand or strands may consist of either solid 50 or hollow conductors or a mixture of both, and the design may change considerably with the electrical requirements. I may also employ wires of any shape, square or flat or round. The prime principle of the invention is the core built of a 55

single piece of wire, formed into loops and helix with strands of wire laid thereon in such a manner that radial and transverse collapse is resisted by the core wire and the wires themselves.

5. I wish it distinctly understood that my hollow core cable herein described and illustrated is in the form in which I desire to construct it and that changes or variations may be made as may be convenient or desirable without departing from 10 the salient features of my invention and I therefore intend the following claims to cover such modifications as naturally fall within the lines of invention.

I claim:

15. 1. In a flexible conductor cable having a large overall cross sectional area relative to its metallic area, a core comprising a continuous wire of helical conformation and formed into circular loops at periodic intervals the axis of the loops and 20 the axis of the helix substantially coinciding.

2. The device of claim 1 with the addition that the plane of the loops is perpendicular to the axis of the helix.

25. 3. The device of claim 1 with the addition that the outside diameter of the loops is the same as the inside diameter of the helix.

30. 4. In a flexible conductor cable having a large overall cross-sectional area relative to its metallic area, a core comprising a continuous wire of helical conformation and formed into circular loops at periodic intervals the axis of the loops and 35 the axis of the helix substantially coinciding, and an annular outer surface of high electric conductivity comprising a plurality of individual conductors stranded thereon.

5. The device of claim 4 with the addition that the stranded individual conductors are stranded on the circular loops in helices parallel to the helical portion of the core.

40. 6. The device of claim 4 with the addition that the individual conductors are hollow.

7. The device of claim 4 with the addition that

individual conductors are solid with hollow conductors in between and that the hollow conductors are compressed to form a notch so as to engage the circular loops.

8. In a flexible conductor cable having a large 5 over-all cross-sectional area relative to its metallic area, a core comprising a continuous wire of helical conformation formed into circular loops, the outside diameter of the loops being the same as the inside diameter of the helix, a plurality of 10 wires stranded about the loops with the same helical conformation as the helical wire thereby resisting radial deformation of the circular loop.

9. The device of claim 8 with some of the 15 stranded wires hollow and of a greater diameter than the remainder of the stranded wires.

10. The device of claim 8 with some of the 20 stranded wires hollow and of a larger diameter than the rest of the strands and compressed forming notches to resist longitudinal displacement of the circular loops along the axis of the cable.

11. In a flexible conductor cable having a large 25 overall cross-sectional area relative to its metallic area, a core comprising a continuous wire of helical conformation and provided with integral circular loops at periodic intervals along the axis of the helix, a plurality of hollow conductors stranded over the loops and laid parallel to the helical portion of the core, said hollow wires being compressed to form notches to engage the 30 loops, and an annular outer surface of high electric conductivity comprising a plurality of individual conductors stranded thereon.

12. The device of claim 11 with the addition 35 that the hollow conductors are so laid upon the wire core that the helices of the conductors parallel the helical portion of the core and abutting the core to resist radial deformation of the circular loops and so engage the loops to resist longitudinal displacement thereof along the axis of 40 the cable.

HORACE A. STAPLES.
